[57] CLAIM

The ornamental design for a computer terminal, substantially as shown and described.

DESCRIPTION

FIG. 1 is a top, front, left side perspective view of a computer terminal showing my new design, the cover being in a closed position;

FIG. 2 is a top plan view thereof on an enlarged scale;

FIG. 3 is a front elevational view thereof on an enlarged scale;

FIG. 4 is a right side elevational view thereof on an enlarged scale;

FIG. 5 is a rear elevational view thereof on an enlarged scale;

FIG. 6 is a bottom plan view thereof on an enlarged scale;

FIG. 7 is a top, front perspective view thereof on a reduced scale, the cover being in an open position;

FIG. 8 is a top, front perspective view thereof on a reduced scale, the cover being in an alternate open position.

The keys are shown in broken lines in FIGS. 7 and 8 for illustrative purposes only.
